Attorney

UNITED STATES PATENT OFFICE.

ALBERT G. WEEKS, OF MINNEAPOLIS, MINNESOTA.

TONE-CONTROL DEVICE.

Application filed January 25, 1927. Serial No. 163,495.

This invention relates to improvements in acoustical devices, having for an object to provide a device for controlling or modulating the sound waves produced by the diaphragms of radio loud speakers and like telephones or of the sound reproducers of phonographs, whereby such waves will possess pure tone values and thereby effect a faithful and accurate reproduction of the sound originally transmitted to the same.

It is also among the prime desiderata of the invention to provide a device of the character mentioned wherein the component parts thereof are so relatively adjusted as to regulate the volume of the sound waves discharged therefrom, hence, rendering the same selective of the particular pitch or tone desired by the user.

It is also amongst the objects of the invention to provide a sound or tone control device which is of unusually simple and rugged construction, thus, a device of marked commercial merit in which the interior thereof is so formed as to produce a reverberating sound chamber functioning with the delivery of sound waves thereto to so modulate said waves that they will ensue from the device with virgin tone values and in faithful reproduction of the originally transmitted sound.

Other objects of the invention will be in part obvious and in part pointed out herein-after.

In order that the invention and its mode of operation may be readily understood by those skilled in the art, I have in the accompanying illustrative drawings and in the detailed following description based thereupon, set out one possible embodiment of the invention.

40 In these drawings:

Figure 1 is a vertical section through the base of a radio loud speaker device showing the improved tone control invention attached to the reproducing unit thereof,

45 Figure 2 is an enlarged longitudinal section through the improved device,

Figure 3 is an end view of the same, and

50 Figure 4 is a longitudinal section through a slightly modified form of the device wherein means are provided for permitting of relative adjustment as between the component parts of the tone control means proper.

Having more particular reference to the drawings, in connection with which like characters of reference will designate corre-

sponding parts throughout, I have shown for purposes of illustration herein, the invention as being adapted to a so-called radio loud speaker device or similar telephone, wherein the base of said device is generally designated 60 by the numeral 1 and the sound amplifying horn thereof by the numeral 2; said base being of a substantially housing like construction and receiving therein the usual sound reproducing unit 3 in a suitable manner. 65 Interposed between this sound reproducing unit 3 and the sound amplifying horn 2 of the loud speaker or other telephone device is my improved tone control means, generally designated for convenience at this time by the 70 numeral 4, the device being preferably enclosed in a casing or housing formed in sections 5 and 6 having interengaging or interfitting parts whereby said sections may be joined in the manner as illustrated in the Figure 2, while nipple-like extensions 7 and 8 are formed upon the opposite ends and concentric portions of the sections 5 and 6, the nipple 7 being connected to the sound outlet 75 way of the reproducing unit 3 whereas the nipple 8 is connected or engaged within the adjacent end of the sound amplifying horn 2.

This casing 4, is preferably formed of material possessing a degree of rigidity which will be prohibitive of vibration to that extent 80 as will create an interference with the sound waves transmitted into the tone control device proper within said casing; it being practicable to construct the casing of certain metals or of certain compositions such as 85 hard rubber, etc., which with the transmission of sound waves thereto, will not vibrate to such an extent as to offer any impediment to the proper functioning and production of pure tone values from the sound control device.

The sound control device proper, may be stated to consist herein of a substantially hollow cylindrical body formed of sections 9 and 10, the section 9 being the body of the device, 100 whereas the section 10 is more in form of a cap-like cover therefor adapted, at times, to have certain adjusting movement with respect to the body, for a purpose which will be subsequently described. That portion of the body 9 of the tone control device receiving the cap-like cover 10 is preferably reduced or shouldered as indicated by the numeral 11, whereby to snugly receive the peripheral portion of the cap 10 thereover and to cause the 105 110

outer peripheral surface of said cap to be flushly arranged with the corresponding peripheral surface of the body as is shown in the Figure 2.

- 5 The chamber formed within the hollow cylindrical tone control device is provided with several openings, such openings being formed in its end walls constituted by the cap 10 and the end of the body portion 9, such openings being designated by the numerals 12 and 13. In this connection, it is to be furthermore noted that the end wall of the body portion 9 is materially thicker than the end wall provided by the cap cover 10 and further, that the inner side of said wall of the body portion 9 is curved throughout its area or concaved or dished as indicated by the numeral 14; the opening 13 being arranged concentrically with respect to this curved or dished portion 14, as is shown in the Figure 2, while the outer portion of said opening is preferably beveled as indicated at 15 whereby to decrease the thickness of the adjacent portions of this particular end wall through which the modulated sound waves are discharged into the transmitting or sound intensifying device, such as the amplifying horn 2. Also, it is of moment to note hereat that the opening 12 within the opposite end wall of the sound chamber within the tone control device is arranged in longitudinal alignment with the opening 13 and concentrically of that particular portion of the cover like cap 10 in which it is formed. Thus, the said opening 12, together with the opening 13 will be arranged approximately concentrically of the respective nipple-like extensions 7 and 8 so that they will effectually function in the receiving and discharging of sound waves into and from the tone control device.
- Through the medium of the chamber formed in the tone control device constituted by the elements 9 and 10 hereinbefore described, I provide an effectual sound reverberating chamber into which the comparatively impure sound waves from the diaphragm of an equipped reproducing device or unit are adapted to be discharged. Because of the reverberatory action of the chamber, those sound waves discharged thereinto, upon being reflected onto the dished or curved end wall 14 will find outlet from the device by way of the opening 13 into the amplifying device 2, such discharging sound waves being of pure or virgin tone values, the pitch of which may be regulated by a user of the device through relative longitudinal adjustment as between the component parts 9 and 10 of the tone control means.
- 60 In the Figure 4, I have shown a slightly modified form of the improved control device. Herein, said device consists of a body portion 9' and a cap-like cover 10', the interengageable parts of said body portion and said cap like cover 10 being formed with

complemental screw threads 16 whereby these latter may be turned onto the former and by such turning, may be longitudinally adjusted so that the opposite end walls of the sound reverberating chamber constituted by the interior of the tone control device will be varied in their respective spacing, and hence, will be rendered selective in the production of sound waves of the desired pitch or volume from said control device.

75 The opposite end walls of the tone control device constituted by the elements 9' and 10' are formed with concentrically arranged and longitudinally aligned inlet and outlet ways 12' and 13', whereas that thickened end wall of the device receiving or having the opening 13' formed therein is dished or curved as indicated at 14'.

75 That the elements 9' and 10' of the modified tone control device may be secured in their relatively adjusted positions for the production of sound waves of the desired pitch or volume, I engage in a screw threaded opening formed in one side of the housing or casting 4' of the attachment, a locking screw 17, the inner end of which is adapted to have binding engagement with an adjacent portion of the body 9' of the tone control device, whereby that particular element will be secured against rotative movement with respect to the cap-like cover elements 10' and consequently thereupon, will serve as a means to retain the opposite end walls of the sound reverberating chamber in their respective fixedly adjusted positions subsequently to an adjustment to the desired or proper nicety.

80 As hereinbefore stated, I have shown for purposes of illustration, my improved tone control device as being adapted for use in connection with the so-called radio loud speaker device. The invention, however, as will be readily appreciated by workers skilled in the art, may be equally well and as advantageously adapted for use in connection with various other sound reproducing devices or telephones or, if desired, it may be advantageously used in connection with sound reproducing devices of phonographs and like intelligence reproducing devices. Furthermore, if desired, the hollow cylindrical tone control device may 110 be made solid, that is, it may be cast in a single piece without the cap like cover element hereinbefore designated by the numerals 10 and 10', although for purposes of permitting adjustment of the device to produce tones or a selective volume or pitch, it is preferable that the device be formed of the body portions and the cap-like cover portions hereinbefore identified. Similarly, various mechanical means or equivalents may be employed in lieu of the means specifically illustrated and described herein for retaining or locking the component parts of the tone control device in relatively adjusted positions.

115 Manifestly, the construction shown is ca- 120

pable of considerable modification and such modification as is within the scope of my claims, I consider within the spirit of my invention.

5 I claim:

1. A tone control device comprising a sectional hollow body having end walls provided with openings, the sections of said body being longitudinally adjustable with respect to each other, means for securing said body sections in relatively adjusted positions, one end wall of said body being thickened and having the inner face thereof dished and the opening in said thickened end wall being arranged concentrically of the dished face.
- 10 2. A tone control device comprising a hollow sectional body having end walls provided with openings, the sections of said body being longitudinally adjustable with respect to each other, means for securing the body sections in relatively adjusted positions, one end wall of said body being thickened and having its inner face dished, the opening in said thickened end wall being arranged concentrically of the dished face thereof, and a rigid casing receiving and supporting said body and having sound inlet and outlet ways therein communicating with the openings in said body.
- 15 3. A tone control device comprising a sectional body, the sections of which are adapted for relative longitudinal adjustment, said body having opposed resonating surfaces formed upon the inner sides of the opposite ends thereof, one of said ends being thickened and having its particular resonating surface formed by dishing said inner side of the same, and each of the ends having concentric openings therein.
- 20 4. A tone control device comprising a sectional hollow body, the sections of which are adapted for relative adjustment, the end wall of one of said sections being thickened and having its inner side dished and a concentric opening formed therein and the end

wall of the remaining section having a plane inner side formed with a concentric opening.

5. A tone control device comprising a hollow body having end walls and constituting an unobstructed chamber, said walls being provided with openings, one end wall having its inner surface dished to form a resonating surface for the greater portion of its area and the opening therein being arranged concentrically of said dished portion.

50 6. A tone control device comprising a hollow body having end walls and constituting an unobstructed chamber, said walls being provided with openings, one end wall of the body being thickened and the inner surface of said end wall being dished and having the opening therein arranged concentrically of the same.

65 7. A tone control device comprising an adjustable sectional hollow body having end walls and constituting an unobstructed chamber, said walls being provided with longitudinally opposed openings, one of said walls being thickened and having its inner face dished, the opening in said thickened end wall being arranged concentrically of the dished face.

70 8. A tone control device comprising a hollow body having end walls and constituting an unobstructed chamber, said end walls having concentric sound admitting and emitting openings and forming opposed resonating surfaces for said chamber, one of the end walls being thickened and having its resonating surface formed by gradually reducing the same towards the opening therein.

75 9. A tone control device comprising a hollow body having end walls and constituting a reverberating chamber, and a casing having sound discharge ways snugly receiving said body and supporting the same against material vibrating motion.

In witness whereof I have hereunto set my hand.

ALBERT G. WEEKS.
